UNITED STATES PATENT OFFICE.

LLOYD D. FREELAND, OF CHICAGO, ILLINOIS, ASSIGNOR TO WILLIAM J. H. STRONG,
OF CHICAGO, ILLINOIS.

DESIGN FOR A FRAME FOR MOTOR-DRIVEN FANS.

47,783.

Specification for Design.

Patented Sept. 7, 1915.

Application filed June 11, 1915. Serial No. 33,602. Term of patent 14 years.

To all whom it may concern:

Be it known that I, LLOYD D. FREELAND, a citizen of the United States, residing at Chicago, in the county of Cook, and State of Illinois, have invented a new, original and ornamental Design for the Frame of a Motor-Driven Fan, of which the following is a specification, reference being had to the accompanying drawing, forming a part thereof.

Figure 1 is a side elevation of the frame of a motor-driven fan showing my new design. Fig. 2 is an end elevation.

I claim:

The ornamental design for the frame of a motor-driven fan, as shown.

LLOYD D. FREELAND.

Witnesses:

GEORGE L. CHINDAHL,
C. PAUL PARKER.
